UNITED STATES PATENT OFFICE.

SAMUEL M. GEHO, OF GRANTSVILLE, WEST VIRGINIA.

HAY AND STRAW STACKER.

1,302,030.

Specification of Letters Patent.

Patented Apr. 29, 1919.

Application filed August 3, 1918. Serial No. 248,171.

To all whom it may concern:

Be it known that I, SAMUEL M. GEHO, a citizen of the United States, residing at Grantsville, in the county of Calhoun and 5 State of West Virginia, have invented certain new and useful Improvements in Hay and Straw Stackers, of which the following is a specification, reference being had to the accompanying drawings.

10 This invention relates to stackers, and particularly to means for building stacks having what may be termed a bee-hive shape.

The general object of the invention is to 15 provide a stack of this character including a form into which straw or hay may be filled, and provide means whereby the straw may be carried to the top of the form and discharged thereinto and which may be adjusted upward as the form is filled.

A further object of the invention is to provide means whereby the sections of the 20 form may be released from engagement with each other to remove it from the stack and means for supporting the other sections on the frame of the machine when it is desired to transport the form and the supporting frame to a new section.

A further object is to improve the details 25 of construction of forms of this character and provide a form which has but little weight and the sections of which may be readily handled.

Other objects will appear in the course of 30 the following description.

My invention is illustrated in the accompanying drawings, wherein:—

Figure 1 is a side elevation of a stacker constructed in accordance with my invention, the supporting frame being lowered to 40 its first position;

Fig. 2 is a like view to Fig. 1 but showing the supporting or elevating frame raised to its second position;

Fig. 3 is an end elevation of the stacker, the reaches 20 being omitted;

Fig. 4 is an elevation of a stack showing the form sections partially removed;

Fig. 5 is a top plan view of one of the reaches;

Fig. 6 is a top plan view of the form;

Fig. 7 is a fragmentary vertical section of one of the form staves or sections;

Fig. 8 is a top plan view of the machine to show the manner in which the form sections are supported when disassembled, the frame bars 13 being in section;

Fig. 9 is an elevation of one of the yokes 37;

Fig. 10 is a fragmentary elevation of the 60 connected frame members 13 showing the knuckled joint between the frame members.

Referring to these drawings, it will be seen that for the purpose of forming the hay or straw into a stack, I provide a form 65 10, which has the general shape of a stack to be made and which is composed of a plurality of sections held in engagement with each other in any suitable manner, as for instance, by one or more detachable bands 70 or hoops 11, preferably having turn-buckles thereon whereby they may be tightened up around the form or whereby the bands may be entirely released from the form. This form may be made of slats, staves or in any 75 other suitable manner, but preferably the form will be made of a plurality of segmental solid sections or blocks *a* from 2 to 4 inches thick and the upper part *b* of each form sections may be made of light staves 80 or of sheet metal. This form is open at the bottom and has lateral openings at the upper portion of the form on opposite sides, as at 12, these openings constituting filling openings and extending downward to the 85 top of the form to any desired distance.

Coacting with this form is a frame composed of opposed sections A and B, each section comprising the slightly curved side beams 13 and suitable braces connecting the 90 side beams and holding them in parallel relation. The side beams of each section are pivotally connected to each other, as by knuckles 14 and 14^a, these knuckles forming hinge joints and being connected by a 95 pintle 15. The lower ends of these frames A and B are supported upon trucks including axles 16 and wheels 17. A hoop 18 surrounds the lower end of the form and is provided with eyes 18^a at a plurality of 100 points. Connected to these eyes are a plurality of telescopic reaches, each reach comprising the sections 19 and 20, as illustrated in Fig. 5. The section 19 is swingingly connected by eye-bolts 21 to the corresponding 105 beam 13 and the section 20 is pivotally con-

nected to the corresponding eye 18^a on the hoop 18 by a shackle or clevis 21^a. The section 19 is longitudinally slotted so that the section 20 may be shifted in this slot and the sections 19 and 20 are provided with alined 5 perforations to receive holding pins 22 to thereby provide for lengthening or shortening these reaches when the frame composed of the sections A and B is lowered to the 10 position shown in Fig. 1 or raised to the position shown in Fig. 2. Pivotally connected to the beams 13 are the tables 23 which may be folded over upon the sections A and B but which when in use extend outward in 15 horizontal planes to receive the hay or straw for forming the stack.

For the purpose of carrying the hay or straw upward upon the frames A and B and discharging the material into the form 20 10, I provide endless belts 24, one disposed in connection with each frame A or B. These belts pass over the rollers 25 and 26 mounted between the members 13. Mounted on the shaft of the roller 26 is a gear wheel 27 which is engaged by a relatively large 25 gear wheel 28 having a crank pin 29. Connecting the crank pins 29 is a connecting rod 30 which is longitudinally slotted as at 31. A pin 32 projects outward from an 30 adjustable pin plate 32^a which is pinned to a head 15^a on the pintle 15 at one end thereof, and the walls of the slot 31 ride on this pin. Power may be applied to the shafts 35 of the rollers 26 in any suitable way. For instance, I have shown on the shaft of the 40 wheel 28 of section A a belt wheel 33 and have shown on the shaft of the roller 26 of section B a fly wheel 34. Power may be applied to the band wheel 33 and it will be obvious that by this means, power may be 45 transmitted to the several rollers and belts and that the belts will move in opposite directions.

The purpose of the pin 32^a in the plate 22 is to prevent the connecting rod from becoming locked on a dead center. It will be noticed that the wrist pins or cranks 29 of the gear wheels 27 are disposed in angular relation to each other and that they 50 rotate in opposite directions so that as one of the gear wheels is moving in a clockwise direction, the other gear wheel will be moving in a counter-clockwise direction. Now as the crank pins 29 near a position 55 where the connecting rod will be on a dead center, one or the other walls of the slot 31 will engage with the pin 32 and will rock upon this pin acting as a lever to shift the driven crank pin 29 past its dead center. At one extremity of movement of the connecting rod the upper wall of the slot 31 will engage this pin and at the other extremity of its movement the other wall of 60 the slot will engage the pin. By this means 65 I drive one of the gears 27 from the other

gear wheel 27 without the use of a train of gear wheels or other complicated mechanism and by this means I secure an opposite movement of rotation for the two rollers 26.

Mounted upon one of the trucks is a windless 70 35 over which passes a cable 36 which engages with the end of the opposite frame. Now when this windless 35 is rotated to wind up the cable 36, assuming that the frames A and B are free or disconnected 75 from the form, then the wheels 16 will be brought nearer to each other, the sections A and B will rotate on their pivotal connections 14 and 14^a and the middle of the sections will, of course, rise. By this means 80 when the form has been filled up to the openings 12, the frames A and B may be shifted nearer to each other and the middle portions of the frames elevated and thus by gradually elevating the middle of the 85 frames A and B, the elevator belts will be raised and thus discharge the straw or hay at higher and higher points into the form. When the form is completely filled, the frame may be raised sufficiently to permit 90 it to shift it away from the form and then the sections of the form may be disconnected from each other and the form taken off of the stack or the sections of the form may be released from engagement with each 95 other when the frame sections A and B have been lifted to their highest point.

Supporting yokes 37 are adapted to be disposed upon and rest on the reaches composed of the sections 19 and 20, these yokes 100 being downwardly bowed and adapted to receive the staves or sections of the form 10 when the form is disassembled and is to be transported from one place to another. When it is desired to build a new stack, the 105 form is again set up within the frame in the position illustrated in Fig. 1, and the operation again performed. Inasmuch as the reaches 19 and 20 are pivotally connected to the frame and are likewise slidably connected to each other, it is obvious that these reaches may be adjusted to suit the degree of angularity between the sections A and B.

It will also be necessary, of course, when the angularity of the sections A and B is 115 changed to remove the connecting rod 30 previously used and substitute therefor a shorter connecting rod. This, of course, necessitates the elevation of the frame sections A and B in two or more stages, there 120 being a shorter connecting rod for each stage. While I have referred to the use of shorter and longer connecting rods, yet it will be obvious that the connecting rod might be so formed as to provide adjustable 125 bearings for the wrist pins or crank pins 29 to thereby change the effective length of the rod. By the mechanism heretofore described it is possible to build a stack very quickly and easily without skilled labor. 130

This is particularly important at the present time when the art of building stacks of this character is gradually going into disuse for lack of trained labor. The form may be 5 readily transported from place to place on the wheeled sections A and B and the form may be readily set up or taken down.

While I have illustrated a form of my invention which I have found to be thoroughly effective in practice, it will be obvious that many changes may be made in the form, without departing from the spirit of the invention, as defined in the appended claims.

Having described my invention, what I claim and desire to secure by Letters Patent is:—

1. A stack former of the character described including a form open at its upper and lower ends and designed to rest upon the ground, a frame coating therewith including two sections pivotally connected to each other at their inner ends, said conjoined ends of the two sections embracing 20 said form and the two sections converging upwardly, and means mounted on the sections for conveying material upward on said sections and discharging it into the upper end of the form.

2. A stack former of the character described including a form open at its upper and lower ends and designed to rest upon the ground, a frame coating therewith including two sections pivotally connected to each other at their inner ends, said conjoined ends of the two sections embracing 25 said form and the two sections converging upwardly, means mounted on the sections for conveying material upward on said sections and discharging it into the upper end of the form.

3. A stack former of the character described including a form open at its upper and lower ends, and a frame coating therewith composed of two sections pivotally connected to each other at their inner ends, 30 wheels supporting the outer ends of the sections, elevator belts mounted upon said sections and adapted to discharge into the upper end of the form, means whereby the elevator belts may be driven, means for engaging the lower ends of the sections with the base of the form, and means whereby the lower ends of the sections may be shifted toward or from the form to thereby raise the middle of the form and the upper ends of 35 the elevator belts.

4. A stack former of the character described comprising a form composed of detachable sections and having filling openings at its upper end, and a supporting frame for 40 the form composed of two sections pivoted

to each other in alinement with the axial plane of the form, elevator belts mounted upon the sections, means for driving the elevator belts in opposite directions, and means whereby the outer ends of the two sections 70 may be shifted toward each other to thereby carry the elevator belts upward as the form is filled.

5. A stack former of the character described comprising a form made in a plurality of detachable sections open at its lower end and having receiving openings in its upper end, a frame formed of two downwardly and outwardly inclined sections, the sections being pivoted to each other at their 80 upper ends, wheeled trucks supporting the lower ends of the sections, means whereby the lower ends of the sections may be drawn toward each other to thereby elevate the connected ends of the sections, endless conveyors 85 mounted upon the sections and discharging into the receiving openings of the form, and power operated gearing for driving said endless conveyors.

6. A stack former of the character described comprising a form made in a plurality of detachable sections open at its lower end and having receiving openings in its upper end, a frame formed of two downwardly and outwardly inclined sections, the sections 90 being pivoted to each other at their upper ends and adapted for detachable engagement with the form at their upper ends, wheeled trucks supporting the lower ends of the sections, means whereby the lower ends 95 of the sections may be drawn toward each other to thereby elevate the connected ends of the sections, endless conveyors mounted upon the sections and discharging into the receiving openings of the form, and power operated gearing for driving said 100 endless conveyors, including driving shafts for the conveyors having gear wheels and wrist pins, the wrist pins of the gear wheels being disposed in opposed relation, a connecting 110 rod connecting said wrist pins, and a fulcrum with which said connecting rod engages upon each reciprocation at the extremity of its movement in one or the other direction to thereby cause the connecting rod 115 to pass the dead center of the wrist pins.

7. A stack former of the character described comprising a form made up of a plurality of segmental sections, the form being open at its lower end and having receiving 120 openings at its upper end, an elevating and supporting frame formed of two downwardly and outwardly inclined sections pivoted to each other at their upper ends and embracing the form at their upper ends 125 when the form rests upon the ground, wheeled trucks supporting the lower ends of the sections, an annular band surrounding the lower portion of the form and adapted to engage therewith and having eyes, and ex- 130

21
tensible reaches connected to the eyes and to the two sections of the frame, means whereby the lower ends of the frame sections may be drawn toward each other to thereby elevate the connected ends of the sections, endless conveyers mounted upon each of said frame sections and discharging at their upper ends into the receiving openings of the

form, and power operated means for operating said endless conveyer. 10

In testimony whereof I hereunto affix my signature in the presence of two witnesses.

SAMUEL M. GEHO.
